UNITED STATES PATENT OFFICE.

FRANK NEARING, OF NEW YORK, N. Y.

ROTARY ENGINE.

1,071,779.

Specification of Letters Patent.

Patented Sept. 2, 1913.

Application filed April 21, 1913. Serial No. 762,691.

To all whom it may concern:

Be it known that I, FRANK NEARING, a citizen of the United States, residing at 211 Columbus avenue, borough of Manhattan, 5 city of New York, county of New York, and State of New York, have invented a new and useful Rotary Engine, of which the following is a specification.

My invention relates to improvements in rotary engines; said engines to be operated by steam or any vapor, gas explosive or otherwise, or liquid, in which there are two cylinders in the same plane with coupled shafts, the said cylinders being set on a rigid base; upon said shafts are fixed drums each with a piston, said pistons being on opposite sides of the shaft. And the objects of my improvements are, in a rotary engine; first, a valveless, balanced, adjustable pressure inlet. Second: the prevention of pressure leakage between pistons and cylinder heads. Third: the eccentric disks shaped so as to close the abutments with the least degree of revolution between the passage of the pistons and the seating of the abutments, and to obtain the action of pressure throughout a greater portion of the revolution. Fourth: to prevent the unnecessary wear of the abutments during their movement. Fifth: to prevent loss of pressure through the abutment entries. Sixth: to insure the free return of the abutment into its chamber. Seventh: to simplify the cross heads and guides as there is no pressure on the abutments during movement, and consequently very little friction on the guides.

I attain these objects by the mechanism illustrated in the accompanying drawings.

Figure 1 is a side elevation of the machine showing the disks, the cross heads and guides, the lever shafts and gears for throwing the pressure cut-off. Figs. 2, 3 and 4 show the improved piston wing. Fig. 2 shows the complete wing with spring for pressing the two parts against the cylinder heads. Fig. 3 shows a side view of one half. Fig. 4 shows a view of one half looking from the bottom of same. The parts shaded show where cut away for interlap. Fig. 5 shows the end of cylinder showing the pressure inlet, the lever and toothed arc for throwing the cut-off, and the geared arc and pinion for connecting the lever to the cut-off valve. Fig. 6, shows the back of the abutments with the guide and relief grooves. Fig. 7 shows the guides with yokes. Fig. 8,

shows the engine in plan view, the pressure pipes, the cut-off lever, gears and shaft, and the eccentric disks with the top one cut away to show the increased circular portion and 60 the eccentric portion of the lower disk. Fig. 9, is a section across cylinder, showing the inlet ports with the drum cut away to take pressure at both ends. Fig. 10, shows the inside face of cylinder head cut away over 65 the cut-off valve and gear connection, and shows the opening to the blow-back valve. Fig. 11, is a cross section through the cylinder near the end showing the drum as chamfered and cut away for pressure inlet, 70 the abutment with guide and relief groove and the piston. Fig. 12, is a section across abutment, cylinder head and flange of abutment chamber, showing the blow-back valve and the pressure inlet for same. 75

Similar letters refer to similar parts throughout the entire views.

B represents the base consisting of a channel section of steel or other equally strong material. At equal distances from the center are the two cylinders C'. C'. connected by the coupled shafts S'. S'. upon which shafts within the cylinders C'. C'. are set the drums J² which are chamfered or cut away at each end to admit pressure from 80 the circular segmental ports P², the outer edges of which being of somewhat less radius than the perimeter of the drums J². The ports P² are in the cylinder heads C³ and are connected by openings to the inlet 85 pipes P., which are connected to both heads of both cylinders. The cut-off valves G³ are shaped to close up the desired portions of the ports P², and are rabbeted on the outer and inner sides and slide in grooves recessed 95 within the cylinder heads C³, the outer edges of the cut-off valves G³ are provided with teeth connecting gear wheels G⁴, also within the cylinder heads C³, the gear wheels G⁴ are mounted on shafts S⁴ which run through 100 the cylinder heads, these shafts S⁴ also carry other gear wheels G⁵, which engage the segments G⁶ which are fixed on the shaft S³, the lever Z' is also fixed on the shaft S³, which thereby moves all the cut-off valves 105 G³ and is provided with the toothed arc Z⁴, together with the clutch and connecting rod Z², and handle Z³, and spring Y⁵ for holding the cut-off valves G³ in the desired position. The portion of the pistons E³ and E⁴, 110 which are mounted on the drums J² are inclined at about the same angle with the

radius of the cylinder as the abutments, and are each in three parts, the parts E^4 being fixed to the drums J^2 , the movable parts E^3 are halved and interlapped and provided 5 with springs Y^4 in the openings in the middle, which press the two parts of each completed wing longitudinally against the cylinder heads, and the spring Y^3 presses the same radially against the inner sides of the 10 cylinders C' , C' .

Between the cylinders C' are the two bearing stands D' , D' , which are extended toward the center and upon the top of which are mounted the guides L^4 for the lower 15 cross heads. These guides are plain bars of greater width at the side which bear against the cross heads L^3 and support the cross heads L^3 which are shaped to fit and slide freely on the said guides L^4 . The bearing stands D^2 , D^2 for supporting the outer ends 20 of the shaft S' are set outside and near the cylinders.

D^3 at the center is the lower bearing of the perpendicular shaft S^2 .

25 D^4 is the top bearing of the shaft S^2 .

D^5 is the bearing for shaft S^2 .

Between the cylinders C' , C' and the bearing stands D' , D' are the couplings K , K , which are packed somewhat apart.

30 On and near the center of the main shaft S' is set the bevel gear G' , which engages with a similar bevel gear G^2 on the perpendicular shaft S^2 , which gears operate the disks F^3 and F^4 , which in turn push against

35 the rollers N , N , N , N , causing the cross heads L^3 , L^3 , L^3 , L^3 to move forward and back upon the guides L^4 , L^4 , L^4 , L^4 , the rods R , R , R , R , holding the cross heads so that

40 the rollers are constantly against the rims of the disks. At one end of each rod is a spring Y' permitting a slight variation in case of a little inequality in the distance across the eccentric portion of the disks. The cross heads L^3 are shaped to fit the

45 guides L^4 which are plain bars, the lower ones wider on the upper sides, set on the bearing stands D' , D , and the upper set of guides which work on the disk F^3 are wider on the lower sides and are secured to the

50 top brace B^2 . The abutment chambers or cases A^4 are fixed to the cylinder heads and provide support and bearing for the abutments and are provided with grooves in the back side to allow accumulated pressure to escape during the withdrawal of said abutments.

55 The abutment A^5 is in two parts. The upper part A^3 is removable and is set on pins at each end and is pressed downward 60 by the spring G^2 to hold the lower portion A^5 firmly against the drum J^2 , and the abutments A^5 are also provided with grooves on the back side fitting a guide A^7 set in the abutment slots in cylinders C' , 65 which guides hold the abutment A^5 slightly

away from the drum J^2 during the movement of the said abutments, but allows the spring Y^2 to press it against the drum when seated, the said grooves and guides being both inclined somewhat so that their support is withdrawn at the end of the stroke, and the abutment rests firmly against the drum J^2 , thus preventing unequal wear by grinding on both the abutment A^5 and the drum J^2 .

70 There is a groove in the back side of the abutment A^5 for a middle portion of its length, and a corresponding groove opposite in the abutment case, but not through the cylinder heads; so as to allow accumulated pressure to escape from the abutment case during the withdrawal of the abutment.

75 Between the cylinder heads and the flanges of the abutment chambers are valves A^6 , which work in ways formed to hold them.

80 These valves consist of flat plates of the same width as the openings in the cylinder heads leading to the abutment chambers, and are set perpendicular to the abutment.

85 The edges of these plates farthest from the abutments are beveled and face openings from the inner face of cylinder heads C^3 , which allow the pressure, when applied, to

90 enter said opening and force the valve A^6 firmly against the abutment, preventing thereby the leakage of pressure through the abutment entry. This pressure is withdrawn by the exhaust.

95 T represents the cover to the outer abutment slots.

100 V represents an opening in cylinders at a point where there is no action.

A brace B^2 , B^2 made of two angles connects the cylinder at top. Upon this brace is mounted the upper bearing of the perpendicular shaft S^2 , which bearing is marked D^4 , and the guides L^4 for the cross heads working on the disk F^3 are also fixed

105 between the two angles forming the brace B^2 . The yokes Y to which the rods are attached, are firmly fixed to the cross heads, one pair of rods being separated sufficiently to clear the other pair.

110 In operation the pressure enters the first cylinder through the pipes P and through the circular ports and entrances cut away at each end of drums at both ends simultaneously, pressing against the piston of

115 that cylinder and forcing the said piston around through a portion of its revolution until the exhaust X is reached. Before this

120 point is reached the abutment of the second cylinder is seated, and the second cylinder has taken the pressure, as both disks are circular for somewhat more than a semi-circle, and both cylinders are in action before the first one has exhausted during every revolution.

125 The segmental ports may be shortened by the movement of the cut-off valve which is adjusted and held by the le-

ver Z and the toothed arc Z⁴. The abutments A⁵ are supported by the guides until the cylinder is closed, at which point the incline on guide, and also in abutment 5 groove allows the abutment to rest upon the drum. As the pressure is applied it acts on the end of the valve A⁶, pressing it firmly against the abutment and preventing any escape into the abutment chamber. As 10 the abutment is withdrawn a groove on the underside of same and a groove opposite in the abutment case acts as a relief against any compression in the abutment chamber.

Having thus described my invention, 15 which I claim is new, and desire to secure by Letters Patent is:

1. In a rotary engine the combination of the two cylinders mounted on a rigid base and provided with intake ports taking pressure 20 automatically through both heads of each cylinder in turn for the desired degree of revolution, and exhaust ports and movable abutments of the coupled shafts mounted in independent bearings and carrying 25 within said cylinders drums having pistons capable of radial and longitudinal expansion, mounted thereon, substantially as shown and described.

2. A rotary engine comprising a cylinder 30 containing a longitudinal sliding abutment and having mounted therein a horizontal

shaft carrying a three part piston in combination with a vertical shaft carrying two eccentric disks and connected with said horizontal shaft by means of bevel gears, one of said disks being flattened for a smaller portion of its perimeter, while the other has a corresponding portion of increased radius and connecting means whereby the rotation of said disks causes the reciprocation of said abutment, substantially 35 as shown and described.

3. In a rotary engine having a cylinder containing a longitudinally moving abutment, provided with a supporting guide, a valve to prevent pressure escape and relief, 40 grooves, the mechanism for operating said abutment consisting of the vertical shafts; the eccentric disks mounted thereon; the friction rollers bearing against said disks 45 and mounted on cross heads moving on guides, and the rods connecting the cross heads on one side of one disk with the cross heads on the opposite side of the other disk, whereby the rollers are held constantly 50 against the edges of said disks, substantially 55 as shown and described.
